PNEUMATIC SANDER

Lowell N. Brown, Creve Coeur, Mo., assignor to General Products Corporation, St. Louis, Mo., a corporation of Missouri

Filed June 4, 1963, Ser. No. 75,203

Term of patent 14 years

(Cl. D37—1)

The broken line disclosure of a fragmentary portion of air hose and of a coupling is for illustrative purposes only.

I claim:

The ornamental design for a pneumatic sander, substantially as shown and described.
